CLAIM

The ornamental design for a hair color package with surface ornamentation, as shown and described.

DESCRIPTION

FIG. 1 is a perspective view of a first embodiment of a hair color package with surface ornamentation embodying our new design;

FIG. 2 is a top view thereof;

FIG. 3 is a front view thereof;

FIG. 4 is a right side view thereof;

FIG. 5 is a bottom view thereof;

FIG. 6 is a rear view thereof;

FIG. 7 is a left side view thereof;

FIG. 8 is a perspective view of a second embodiment of a hair color package with surface ornamentation embodying our new design;

FIG. 9 is a top view thereof;

FIG. 10 is a front view thereof;

FIG. 11 is a right side view thereof;

FIG. 12 is a bottom view thereof;

FIG. 13 is a rear view thereof; and,

FIG. 14 is a left side view thereof.

Broken lines are included herein to depict environmental subject matter and form no part of the claimed design.
